UNITED STATES PATENT OFFICE.

THOMAS W. DOWRIE, OF PONTIAC, ILLINOIS, ASSIGNOR OF ONE-HALF TO
CHARLES W. ST. JOHN, OF SAME PLACE.

HEEL-MACHINE.

SPECIFICATION forming part of Letters Patent No. 443,162, dated December 23, 1890.

Application filed August 5, 1890. Serial No. 361,043. (No model.)

To all whom it may concern:

Be it known that I, THOMAS W. DOWRIE, a citizen of the United States, residing at Pontiac, in the county of Livingston and State of Illinois, have invented a new and useful Heel-Building Machine, of which the following is a specification.

This invention has relation to a heel-building machine for use by shoe-makers and manufacturers.

The objects in view are to provide a machine into which a series of lifts or portions of lifts may be inserted for the purpose of building up a heel, which machine is adapted to maintain the straps or lifts in snug position while being fastened and to indicate the height of the heel.

Other objects and advantages of the invention will hereinafter appear, and the novel features thereof will be particularly pointed out in the claims.

Referring to the drawings, Figure 1 is a perspective of a machine constructed in accordance with my invention, the same being applied to a bench and shown in operation or in the act of building up a heel. Fig. 2 is a perspective in detail of the casting. Fig. 3 is a vertical longitudinal section of the machine removed from the bench.

Like numerals indicate like parts in all the figures of the drawings.

1 designates the anvil or base of my machine, which is preferably of cube shape and formed of cast metal. At the rear side of the anvil there is formed integral therewith or secured thereto a vertical standard 2, bifurcated from its upper edge to a point on a level with the upper surface of the base 1, and thereby forming a vertical guide 3. Below the base 30 the standard is thickened and the vertical guide 3 is continued to the bottom of the standard in the form of a cylindrical opening 4.

Mounted for reciprocation in the opening 4 is a rod 5, and encircling the same is a coiled spring 6, the lower end of which rests upon a shoulder 7, located near the lower end of said opening. The upper end of the rod is provided with a horizontally-disposed U-shaped

presser-plate 9. The rear end of the plate 9 is provided with a square shank 10, which loosely fits between the ways 3. The inner edge of the plate 9 is preferably beveled, as shown, and the general contour of the plate is such as when lowered upon a heel in the course of construction of the same to have contact with said heel near the edges thereof. Above the presser-plate 9 there is secured to the end of the rod a vertical indicating-standard 11, the upper end of which carries an indicating-finger 12, which moves over a graduated scale of inches 13, displayed upon the front face of one of the edges of the guide 3. The coiled spring which encircles the rod 5 is designed to normally elevate said rod until the indicating-finger is opposite the zero-point.

In employing the apparatus I prefer to mount the same upon an ordinary bench 14, astride which a workman may sit, and through the bench depends the rod 5, which has its lower end bent to form a hook. A pair of bearing-ears 15 is secured to the floor under the bench, and in the same is pivoted a foot-lever 16, connected to the bent end of the rod 5 by means of a link 17. The lifts are placed or piled under the presser-plate 9 upon the base, and when a sufficient number of lifts have been assembled or thought to be so assembled by the workman the foot-lever is depressed, so as to bring the plate 9 upon the lifts and the pointed arm or finger 12 will indicate upon the scale the height of the heel. If the height is too great, a lift is removed or a portion thereof, and if too small a lift or a portion of a lift is added. When the thickness has been accurately obtained, the presser-plate is held snugly down upon the pile of lifts and two or three nails driven through said pile, whereby they are secured together and are ready for application to the shoe, after which they are shaped.

From the above description it will be apparent that heels of a uniform predetermined thickness may be rapidly formed and securely held along their edges while connected, and that heels may be built up of scraps or small

pieces of leather, thereby effecting a saving, and at the same time producing a very secure heel.

Having described my invention, what I claim is—

1. The combination, with the anvil having a rear vertically-slotted standard, of the U-shaped presser-plate extending over the anvil and provided at its rear end with a head or shank mounted for vertical movement in the slot, a support for the anvil, a foot-lever, a rod connecting the same with the shank or head of the presser-plate, and a spring for normally raising the same, substantially as specified.

2. The combination, with the anvil provided with a vertical standard at the rear side thereof, which standard is provided with a guide, and at one side thereof with a scale, of a rod mounted for movement in the guide, having a spring for normally elevating the same, a presser-plate extending from the rod, and an indicating-finger also extending from said rod, substantially as specified.

3. The combination, with the bench, of the anvil mounted thereon, the vertical standard having the partially slotted and perforated guide, the rod mounted therein for reciprocation, a foot-lever located under the bench and loosely connected with the lower end of the rod, a U-shaped plate having a square shank connected to the rod above the anvil, and an indicating-standard having an indicating-arm connected to the upper end of the rod above the plate and moving over a scale formed on the standard, and a coiled spring encircling the rod between the plate and a shoulder formed at the lower end of the guide-opening, substantially as specified.

In testimony that I claim the foregoing as my own I have hereto affixed my signature in presence of two witnesses.

THOMAS W. DOWRIE.
